UNITED STATES PATENT OFFICE.

ELLSWORTH A. HAWTHORNE, OF BRIDGEPORT, CONNECTICUT.

LIGHTING APPARATUS.

1,090,980.

Specification of Letters Patent. Patented Mar. 24, 1914.

Application filed December 6, 1912. Serial No. 735,185.

To all whom it may concern:

Be it known that I, ELLSWORTH A. HAWTHORNE, a citizen of the United States, and a resident of Bridgeport, in the county of 5 Fairfield and State of Connecticut, have invented an Improvement in Lighting Apparatus, of which the following description, in connection with the accompanying drawings, is a specification, like characters on 10 the drawings representing like parts.

This invention relates to lighting apparatus, and more especially, though not exclusively, to electric lighting apparatus for motor cycles and other vehicles, and when 15 so employed, shows a red rear light, and illuminates a number plate with a white light.

My invention will be best understood by 20 reference to the following specification, when taken in connection with the accompanying drawings of one illustrative embodiment thereof, while its scope will be more particularly pointed out in the appended claims.

In the drawings:—Figure 1 is a rear elevation of a lighting apparatus embodying my invention, a number plate being indicated in dotted lines; Fig. 2 is a side elevation, partly broken away, and partly shown in section, of the lighting apparatus, showing the number plate in dotted lines; Fig. 3 is a plan view of the apparatus on an enlarged scale, partly broken away and partly in horizontal section; and Fig. 4 is a sectional view on line 4—4 of Fig. 3, looking 35 toward the right.

Referring to the drawings and to the embodiment of my invention which I have there shown for illustrative purposes, 5 is a supporting bracket having a general form 40 of a right angle, and provided with attaching ears 6 and 7, which may be attached to any convenient part of the motor cycle or other vehicle, as for example to a mud guard 8, the latter being indicated in dotted lines. Suitable means of attachment 45 may be provided, as for example bolts 9 and 10, passing through the ears 6 and 7, respectively, and the mud guard 8. The bracket 5 has a horizontal portion 11, and 50 a vertical portion 12, the latter serving as a support for a number plate 13, indicated in dotted lines, and provided with suitable means of attachment, herein bolts 14 and 15, passing through the bracket. The horizontal 55 portion 11 of the bracket supports a bat-

tery casing 16, the latter being partially encircled by an attaching member, herein in the form of a strap 17, partially encircling the casing and provided at one end with an offset tongue 18, passing through an aperture 19 in the bracket 5, and interlocking with the latter (see Fig. 4). The other end of the strap may be provided with suitable means of attachment to the bracket 5, herein comprising a bolt 20, having a wing-nut 21. This serves as a simple, convenient and effective means for clamping the battery casing to the supporting bracket, yet in such a manner that by simply removing the bolt 20, the attaching member 17 may be entirely disconnected from the supporting bracket 5, by withdrawing the offset portion 18 from the aperture 19.

The battery casing 16 may serve to contain any suitable form of battery, but herein contains a dry cell 22 of common form, the latter being electrically connected to an incandescent electric lamp 23, located within a lamp casing 24, and having a usual screw-threaded stem 25, passing through and 75 threaded into the casing 24, strap 17, and casing 16, where it is connected in any suitable manner to the two terminals of the battery. The casing 24 is provided in its under side with an aperture 26, across which 80 may be placed a light-transmitting element 27, in the form of a sheet of mica or glass, while the upper side of the casing is provided interiorly with a light-reflecting surface 28, which serves to reflect the rays of 85 light through the aperture 26 onto the number plate 13, the latter thus being illuminated by both the direct and the reflected rays from the lamp.

The rear wall of the lamp casing 24 is 90 preferably provided with a light-transmitting element 29, herein a red "jewel" of common form, mounted in a supporting frame 30. The latter passes through and 95 is swiveled in an aperture 31 in the rear wall of the casing, and is provided with suitable locking means, herein a pair of radially disposed pins 32, normally out of register with a pair of notches 33 leading from the aperture 31, and when for any reason 100 it is desired to dispense with the red rear light, the "jewel" may be conveniently removed by simply rotating the frame 30 to bring the pins 32 into register with the notches 33, after which the pins are with- 105 110

drawn therethrough. This forms an exceedingly simple, convenient and effective means for mounting the red jewel in the lamp casing in such a manner that it may be removed in a moment's time to allow the user to avail himself of the white light. This may be done when the motor-cyclist wishes to make an examination or repairs of the mechanism of the motor-cycle, and 10 in such cases, he simply removes the red jewel as described, and detaches the lamp and battery, merely removing the strap 17, as hereinbefore described.

While I have herein shown and described 15 one specific embodiment of my invention for illustrative purposes, and have disclosed and discussed in detail the construction and arrangement incidental to one specific application thereof, it is to be understood that the invention is limited neither to the mere details or relative arrangement of parts nor to its specific embodiment herein shown, but that extensive deviations from the illustrated form or embodiment of the invention may be made 25 without departing from the principles thereof.

Having thus described my invention, what I claim and desire by Letters Patent 30 to procure is:—

1. In a lighting apparatus, the combination with a supporting bracket, of an electric lamp, a lamp-casing, a battery, a battery-casing, a member to which said casings 35 are attached, and means for detachably attaching said member to said supporting bracket at two points, said battery casing being disposed between said points and embraced by said member and said bracket.

40 2. In a lighting apparatus, the combination with a supporting bracket, of an electric lamp, a lamp-casing, a battery, a battery-casing, an attaching member partially encircling said battery-casing and to which 45 said lamp-casing is attached, and means for

attaching said attaching member to said supporting bracket.

3. In a lighting apparatus, the combination with a supporting bracket, of an electric lamp, a lamp-casing, a battery, a battery-casing, an attaching member holding 50 said casings and interlocked at one point with said bracket, and attaching means for attaching said member at another point to said bracket. 55

4. In a lighting apparatus, the combination with a supporting bracket, of an electric lamp, a lamp-casing, a battery, a battery-casing, an attaching member partially 60 encircling said battery-casing, extending between said casings and attached to said lamp-casing, said member having one end interlocked with said bracket, and means for securing the other end of said member to said bracket. 65

5. In a lighting apparatus, the combination with a supporting bracket, of an electric lamp, a lamp-casing, a battery, a battery-casing, an attaching member partially 70 encircling said battery-casing and extending between said casings, said lamp having a screw-threaded part extending through said lamp-casing, attaching member and battery-casing into electrical connection with said battery, and means for attaching said 75 member to said bracket.

6. In a lighting apparatus, the combination with a supporting bracket, of an electric lamp, a lamp-casing, a battery, a battery-casing, and an attaching member secured to said lamp-casing and forming 80 with said bracket a clamp for clamping said battery-casing.

In testimony whereof, I have signed my name to this specification in the presence of 85 two subscribing witnesses.

ELLSWORTH A. HAWTHORNE.
